(57) **CLAIM**

We claim the ornamental design for a shower head, as shown and described.

DESCRIPTION

FIG. 1 is a front, top, left side perspective view of a shower head showing our new design;

FIG. 2 is a front view thereof;

FIG. 3 is a rear side view thereof;

FIG. 4 is a left side view thereof;

FIG. 5 is a right side view thereof;

FIG. 6 is a top view thereof; and,

FIG. 7 is a bottom view thereof.

The broken lines of the disclosure represent portions of the shower head that form no part of the claimed design.
